DISH FOR FRUIT COCKTAIL

Kenneth S. Scholl, 3774 Cork Place,
South San Francisco, Calif. 94080

Filed July 14, 1972, Ser. No. 271,780

Term of patent 14 years

Int. Cl. D7—01

U.S. Cl. D7—20

Fig. 3

Fig. 1

Fig. 2

FIG. 1 is a side elevational view of a dish for fruit cocktail showing my new design, the side opposite being identical;

FIG. 2 is a front elevational view thereof, the rear being identical; and

FIG. 3 is a top plan view thereof.

The bottom is substantially plain and unornamented.

I claim:

The ornamental design for a dish for fruit cocktail, as shown and described.
